COMPRESSOR PUMP

Claud Fleming Davis, Pineville, Ky.

Application September 24, 1935, Serial No. 41,927

4 Claims. (Cl. 230—139)

My invention consists in new and useful improvements in compressor pumps, and although the principle here involved may be readily applied in connection with various types of pumps, compressors and motors, the apparatus herein-after described is more particularly adapted for use as a compressor pump in connection with electric refrigeration apparatus.

The primary object of my invention is to provide a compressor pump of this type constructed with a minimum of moving parts and one which can be economically manufactured.

Another object of my invention is to provide a device of this character wherein the parts are so constructed and arranged as to be in substantially perfect balance at all times.

It naturally follows that a further object of the invention is the elimination of vibration and consequently the reduction of noise to a minimum.

A still further object is to provide a compressor pump including a substantially elliptical barrel with a cylindrical compressor block located concentrically therein and wherein the sliding heads of the compressor block are constantly maintained in seating engagement with the inner periphery of the barrel by the pressure developed in the unit.

With the above and other objects in view which will appear as the description proceeds, my invention consists in the novel features herein set forth, illustrated in the accompanying drawings and more particularly pointed out in the appended claims.

Referring to the drawings in which numerals of like character designate similar parts throughout the several views,

Fig. 1 is a vertical sectional view of my improved compressor pump assembled.

Fig. 2 is a horizontal section taken on line 2—2 of Fig. 1.

Fig. 3 is a sectional view taken on line 3—3 of Fig. 1.

Fig. 4 is a vertical sectional view taken on line 4—4 of Fig. 3.

Fig. 5 is a perspective view from the upper end of the compressor block, and

Fig. 6 is a similar view from the lower end of the block.

In the drawings, 1 represents a casing preferably hermetically sealed with a suitable cover 2, the lower portion of said casing forming an annular oil reservoir 3. The outer walls of the casing are preferably provided with conventional radiator fins 4 disposed around its periphery.

Within the casing, I provide a vertically disposed electric motor M comprising a stator 5 and a rotor 6, the latter being preferably mounted on a hollow shaft 7 which is supported at its upper end in a suitable bearing member 8 adapted to be screwed into the central portion of the cover 2 as clearly shown in Fig. 1.

The lower end of the shaft 7 is fixed in any suitable manner to the top plate 11 of an elliptical barrel 9 which is horizontally disposed in the lower portion of the casing 1 adjacent the upper extremity of the reservoir 3. The barrel 9 has a cylindrical outer surface but is provided internally with an elliptical chamber 10 closed on its top side by the barrel plate 11 and open at its lower side. In the form of my invention shown in the drawings, this barrel 10 is supported on the raised bottom of the casing 1 and is rotatably mounted in a circular guideway 12 formed on said bottom.

Within the elliptical chamber 10 of the barrel 9, I provide a stationary cylindrical compressor block 13 which is suitably secured in any convenient manner to the adjacent portion of the bottom of casing 1, said block extending vertically to the top of the chamber 10 with a suitable lubricating clearance between its upper extremity and the plate 11. This block 13 is preferably formed from a solid cylindrical piece of metal and is provided centrally with a fluid pressure well 14 open at its top and closed at its bottom.

The periphery of the block 13 is provided at predetermined points with transverse slots or recesses 15 and 16 which extend axially of the block to within a relatively short distance from the walls of the well 14 as shown in Figs. 5 and 6. In these recesses I provide heads 15' and 16', respectively, which are capable of a radial sliding movement and adapted to engage the inner periphery of the elliptical barrel 9 with their outer ends in seating engagement therewith, thereby dividing the ellipse into high pressure sides H and low pressure sides L as shown in Figs. 2 and 3.

An inlet conduit 17 leads from a suitable source of gas or other fluid to be compressed to an inlet opening 18 located in the bottom of the casing 1 preferably concentric with the compressor block 13. An oil passageway 19 connected at one end to an inlet tube 20 in the reservoir 3 places said reservoir in communication with the inlet 18, whereby oil from said reservoir joins a stream of gas or other fluid to be compressed entering the casing through inlet 18.

Adjacent the inlet 18, the underside of the

compressor block is inset as at 21 (Figs. 1 and 6) to form a circular inlet channel for incoming oil and gas. The low pressure sides L of the elliptical chamber 10 are in communication with the channel 21 by means of slots 22 extending through the periphery of the block 13, terminating in ports 23 drilled vertically from the underside of the block 13, said ports 23 communicating with the channel 21 by means of grooves 24. Thus, fluid entering the channel 21 through conduit 17 and oil passageway 19, flows through the grooves 24 into the ports 23 and out through slots 22 into the low side L of the chamber 10.

The high pressure sides H of the elliptical barrel 10 are in communication with the well 14 by means of peripheral slots 25 in the block 13 which open into ports 26 drilled from the top side of the block, grooves 27 leading from the upper extremities of the ports 26 to the well 14. Thus, the compressed fluid from the high sides of the barrel flow from said high sides through slots 25, ports 26 and grooves 27 into the pressure well 14.

In order to constantly maintain a seating engagement of the outer ends of the sliding heads 15' and 16' with the walls of the elliptical chamber 10, I provide ports 37 leading from the pressure well 14 to the recesses 15 and 16, behind the respective heads. Thus these heads are forced radially into seating engagement by the pressure maintained in the well 14. If desired, springs may be employed for this purpose either with or without the pressure ports 37.

The hollow motor shaft 7 forms a discharge conduit 28 open at its lower end in communication with the pressure well 14 and at its upper end through radial passageways 29, into the upper portion of the casing 1. An imperforate baffle plate 30 which is preferably convex in shape is suitably secured in the upper portion of the casing 1 with its outer extremities in slightly spaced relation to the inner walls of the casing 1, said baffle extending substantially across the upper portion of the casing and located just below the passageways 29 in the shaft 7.

An outlet conduit 31 leads from a point under the baffle but above the lower extremity thereof and extends out through the bottom of the casing 1 as shown at 32 in Fig. 1, from whence the compressed fluid is conducted to a suitable point of use.

In order to compensate for wear of the rotary parts, I preferably provide at the upper end of the hollow shaft 7 a coil spring or the like 33 which is interposed between the shaft and the upper end of the bearing member 8, a washer 34 being preferably located between the spring 33 and this shaft. This washer is provided with a central opening 35 whereby oil carried upwardly through the conduit 28 finds its way through the washer and thoroughly lubricates the upper end of the shaft 7.

Having thus described the construction and assembly of my improved compressor pump, its operation is as follows:—

We will assume that the reservoir 3 has been filled to a predetermined level shown in dotted lines in Fig. 1 with a suitable lubricating oil, a glass liquid level gauge 36 being preferably provided to indicate the oil level. The motor is started and the barrel 9 begins to rotate in counterclockwise direction, the compressor block 13 remaining stationary. The rotation of the barrel 9 causes a vacuum to be created in the low pressure sides L of the elliptical chamber

10 behind the heads 15' and 16', whereupon both gas and oil entering the unit through the inlet opening 18, are drawn through the inlet channel 21, across the block through grooves 24, up into ports 23 and out into the low pressure sides L through slots 2. This mixture of oil and gas is then carried around by the revolving barrel to the high pressure sides H where, as the minor part of the ellipse reaches the forward surface of the outwardly forced heads 15' and 16', said mixture is compressed and forced inwardly through slots 25, ports 26 and grooves 27 into the pressure well 14.

It will be noted that during this entire operation, the oil carried with the gas forms a constant film over all adjacent moving parts each half revolution of the barrel 9, thus thoroughly lubricating and protecting said parts. Furthermore, the pressure maintained in the well 14 is applied through openings 37 to the inner sides of the heads 15' and 16', thereby constantly forcing these heads outwardly into seating engagement with the inner periphery of the elliptical barrel 9.

Due to the fact that these heads are continuously moved inwardly and outwardly in the slots or recesses 15 and 16, the oil and gas entering the well 14 are continuously subjected to an agitation and thorough mixing, this compressed mixture being conducted upwardly through the passageway 28 in shaft 7 and discharged therefrom onto the top side of the baffle plate 30.

The oil and gas then separate, the oil running down the top of the baffle and finding its way through the various clearances in the motor parts back to the reservoir 3. The gas substantially free from oil enters the upper end of the outlet conduit 31 and is conducted to the refrigerating unit or other point of use.

While I have shown and described a device wherein the barrel is rotatable with respect to the compressor block, it is to be understood that I do not intend to confine myself to this particular form of structure. In other words, I may, within the scope of this invention, employ a stationary barrel with a rotary block. Furthermore, while I have shown and described a hermetically sealed casing enclosing both motor and compressor, the basic features of my compressor unit may be employed with equal effect in connection with a device driven either directly or indirectly by a motor located within or without the casing.

From the foregoing it is believed that my invention may be readily understood by those skilled in the art without further description, it being borne in mind that numerous changes may be made in the details disclosed without departing from the spirit of my invention as set out in the following claims.

What I claim and desire to secure by Letters Patent is:—

1. In a motor compressor unit, an hermetically sealed casing, a truly elliptical barrel, a cylindrical compressor block concentrically disposed in said barrel, an electric motor in said casing for rotating one of said members with respect to the other, a pressure fluid well centrally located in said block, transverse recesses in the periphery of said block, radially slidable heads in said recesses adapted to seat against the inner periphery of said barrel and dividing the ellipse into high and low pressure sides, a fluid inlet adjacent said block, a passageway through said block from said inlet to said low pressure side, a passageway

through said block from said high pressure side to said well, a discharge conduit leading from said well through the motor shaft and opening in communication with the upper portion of said casing, a baffle plate in the upper portion of said casing below the opening of said discharge conduit, and a discharge passageway extending from a point below said baffle to the exterior of said casing.

10 2. In a compressor pump, a casing, a fluid inlet in the bottom of said casing, a truly elliptical barrel, a cylindrical compressor block concentrically disposed in said barrel, said compressor block comprising a cylindrical body drilled centrally in an axial direction from its upper side to form a pressure fluid well, and drilled concentrically with said well from its underside to form an inlet channel in communication with said fluid inlet, transverse recesses in the periphery of said block, radially movable heads in said recesses adapted to seat against the inner periphery of said barrel and dividing the ellipse into high and low pressure sides, vertical passageways drilled from the underside of said block to a predetermined depth, means for connecting said passageways with said inlet channel and low pressure sides of the barrel, vertical passageways drilled from the top of said block to a predetermined depth, and means for connecting said passageways with said well and the high pressure sides of said barrel, and a discharge conduit for compressed fluid leading from said well.

3. In a motor compressor unit, an hermetically sealed casing, a vertical electric motor in said casing, a hollow motor shaft, a truly elliptical barrel integral with said shaft and communicating with the interior thereof, a stationary cylindrical compressor block concentrically disposed in said barrel, a pressure fluid well centrally disposed in said block and in communication with the hollow of said shaft, transverse recesses in the periphery of said block, radially movable heads in said recesses adapted to engage the inner periphery of said barrel and dividing said ellipse into high and low pressure sides, means for constantly forcing said heads outwardly, a fluid inlet in the casing adjacent the underside of said block, a passageway through said block from said inlet to said low pressure side, a passageway through said block from said high pressure side to said well, means placing the upper end of said hollow shaft and in turn said well in communication with said casing, and a discharge passageway leading from said casing.

4. A motor compressor unit as claimed in claim 3 including a lubricating oil reservoir in the lower portion of said casing, means for circulating said lubricating oil with the fluid to be compressed through said unit, and means for separating said lubricating oil from the compressed fluid and for returning the same to said reservoir.

CLAUD FLEMING DAVIS.
